 tion of Delaware

Application March 1, 1946, Serial No. 651,173

29 Claims. (Cl. 49—22)

1

The present invention relates to an automatic cupping machine. It has to do, more particularly, with an improved machine or apparatus for cupping or shaping glassware, such as glass tumblers, as they are moved along or transported on a conveyer, such as a glazer conveyor, after issuing from a forming machine or press.

One of the objects of the present invention is to provide an improved machine or apparatus for rapidly cupping or shaping a plurality of glass tumblers as they are being transported on a conveyer without impeding or interrupting the continuous movement or travel of the tumblers.

Another object of the invention is to provide improved means of the foregoing character which may be of portable nature capable of being moved into position to cooperate with a conveyer, such as a moving glazer conveyer, to perform the desired cupping or shaping operation on tumblers being transported by the conveyer.

A further object of the invention is to provide an improved automatic cupping machine or apparatus having cam-actuated means and crank means for moving the tumbler cupping head or heads through a complete cycle of movement into engagement with a tumbler or tumblers to cup or shape the same while traveling along with the moving tumblers and for returning the cupping head or heads to the starting position at the completion of a cycle in readiness for engagement and travel with the next successive tumbler or tumblers to perform the cupping or shaping operation thereupon.

Another object of the invention is to provide an improved automatic cupping or shaping machine or apparatus having improved means for engagement with successive moving tumblers to apply an inwardly directed rotating mechanical force to the exterior of the upper portions of the tumblers to shape or cup the same while being held in predetermined fixed positions on a traveling or moving conveyer.

In the prior art it has been the practice when cupping or shaping tumblers or other glassware, to apply mechanical pressure to the interior of the tumbler walls to force them outwardly into the desired shape. Such practice had the disadvantage of requiring the use of complicated and expensive mechanical means for carrying out the cupping or shaping operation. Other means employed consisted of cup-like heads which were forced by air pressure onto and over the top portions of tumblers to press the same into the desired shape. In accordance with the present invention rotating heads with a series of substan-

2

tially frusto-conical rapidly rotating rollers are moved into contact with tumblers to shape or cup the same by the application of mechanical force exerted by the rapidly rotating rollers to the exterior of the upper portions of the tumblers in downward and inward directions, with the heads and rollers being advanced or traveling in timed relation to the travel of the tumblers. The rotating heads with their rapidly rotating rollers are carried by suitable movable and adjustable frame portions of the cupping or shaping machine or apparatus which extend upwardly from the base thereof, the base being preferably mounted upon suitable supporting casters, thus permitting the entire machine or apparatus to be moved about from place to place when and if desirable. Power driven cam-actuated means and crank means form a part of the machine for moving the cupping heads and their associated parts into engagement with tumblers moving on a conveyer, to cause the heads to travel along with the tumblers as they are moved by the conveyer, to remove the cupping heads from engagement with the tumblers at the end of the forward travel of the cupping heads, and to return the cupping heads at an increased rate of speed to the starting point in readiness for engagement with successive tumblers. Thus, the cam-actuated means and crank means together serve to propel the cupping heads through a complete cycle of movement during which the tumblers are cupped or shaped.

Another object of the present invention is to provide an improved machine or apparatus of the foregoing character wherein the cupping heads may be maintained in elevated position at predetermined times and out of contact with the tumblers to be cupped or shaped, while permitting the heads and their associated cupping rollers to continue to rotate.

The foregoing and other objects and advantages of the present invention will appear from the following description and appended claims when considered in conjunction with the accompanying drawings forming a part of this specification wherein like reference characters designate corresponding parts in the several views.

In said drawings:

50 Fig. 1 is an end elevational view of a cupping or shaping machine embodying the present invention and shown in operative relationship with the conveyer of a glazer for glassware.

55 Fig. 1a is an enlarged fragmentary detail horizontal sectional view, taken substantially along

the line 1a—1a of Fig. 1, looking in the direction of the arrows.

Fig. 2 is an elevational view of the back side of the machine shown in Fig. 1, taken substantially along the line 2—2 of Fig. 1, looking in the direction of the arrows.

Fig. 3 is a top plan view of the machine of the preceding figures.

Fig. 4 is a fragmentary elevational view taken substantially along the line 4—4 of Fig. 1, looking in the direction of the arrows.

Fig. 5 is a vertical sectional view taken substantially along the line 5—5 of Fig. 3, looking in the direction of the arrows.

Fig. 6 is an enlarged fragmentary detail vertical sectional view through one of the cupping heads of the preceding views.

Fig. 7 is a perspective view looking toward the front side of the machine with certain of the parts omitted and showing one of the pair of cupping heads embodying the present invention.

Fig. 8 is a horizontal sectional view taken substantially along the line 8—8 of Fig. 6, looking in the direction of the arrows.

Fig. 9 is a schematic view illustrating the path of movement of the pair of cupping heads of the machine embodying the invention during a complete cycle of operation.

Fig. 10 is an enlarged schematic view generally similar to Fig. 9, illustrating in detail the path of movement and the progressive positions of the parts during a cycle of one of the cupping heads.

Fig. 11 is a layout illustrating the progressive movement of the cam, crank arm, and counterbalance wheel for controlling the operation of the cupping heads of the machine; and

Fig. 12 is a schematic view illustrating the rotary movement of the cupping heads and the independent rotary movement of the cupping rollers during the progressive movement of the heads with the work.

Before explaining in detail the present invention it is to be understood that the invention is not limited in its application to the detail of construction and arrangement of parts illustrated in the accompanying drawings, since the invention is capable of other embodiments and of being practiced or carried out in various ways. It is to be understood also that the phraseology or terminology employed herein is for the purpose of description and not of limitation, and it is not intended to limit the invention herein claimed beyond the requirements of the prior art.

Referring now to the drawings and particularly to Figs. 1 to 7, inclusive, thereof, there is shown one form of machine or apparatus embodying the present invention. In its present form, the machine or apparatus is of portable nature capable of being moved, as a unit, from place to place over a supporting surface, permitting the machine or apparatus to be moved into cooperative relationship with a conveyor, such as a moving endless conveyor of a glazer, whereby the machine is capable of performing a cupping or shaping operation upon a succession of tumblers or other glassware carried and being moved by the glazer conveyor.

As shown, the machine or apparatus comprises a supporting base 15 upon which a sub-base or frame structure 16 is mounted. The sub-base 16 carries an upright standard or frame portion 17 which, in turn, supports a crosshead or horizontally disposed frame structure, shown as a whole at 18. The crosshead 18 is provided at one of

its ends with a pair of rotatable depending cupping or shaping heads 19.

The structure above described is, as shown, of portable nature, the supporting base 15 being provided with casters or rollers 15a. These casters permit the machine or apparatus to be moved over a supporting surface when and if desirable. When the machine has been moved to the desired location, jack screws 15b, one such being located at each corner of the supporting base 15, may be lowered or moved into contact with the supporting surface to thus elevate the machine and the casters 15a to bring the latter out of contact with the supporting surface.

The entire machine or apparatus may be adjusted longitudinally of the supporting base 15 by means of an adjusting screw 20 carried by a sprocket 21, the screw 20 being mounted in an upright fixed supporting bracket 22 carried by the base 15. The bracket 22 carries a driving sprocket 23 mounted upon a shaft having a crank handle 24, the sprockets 21 and 23 being drivingly connected together by a sprocket chain 25. Thus, by turning the crank handle 24, the screw shaft 20 is turned to move the sub-frame 16 toward or away from the bracket 22, dependent upon the direction of rotation of the crank handle. The sub-frame 16 is guided during its longitudinal adjustment on the base 15 by means of keepers or guide members 26.

The upright standard or frame portion 17 carries at one side thereof a vertically disposed guide 17a for engaging and guiding a vertically reciprocable slide 18a depending from and forming a part of the crosshead 18. A slide block 18b is associated with the slide 18a.

The sub-frame 16 carries at its upper portion a pair of transversely spaced horizontally disposed bearings 27 which support a transversely extending crankshaft 28. The crankshaft carries at one end a crank arm 28a connected in suitable manner to a connecting rod 29. The upper end of the connecting rod 29 is bifurcated or forked at 29a, see Figs. 2 and 7, and receives and supports a connecting rod block 18c which is connected by a pin or the like to the slide block 18b. The members 18a, 18b and 18c are adapted to be vertically reciprocated relative to the guide 17a and as a unit with the crosshead 18 when the crankshaft 28 is driven. Moreover, the slide block 18b is adapted to be vertically adjusted relative to the slide 18a by means of a threaded shaft 30. Thus, it will be seen, that the crosshead 18 may be raised and lowered relative to the upright standard or frame portion 17 and the guide 17a when the crankshaft 28, crank arm 28a and the connecting rod 29 are driven. By virtue of a swinging block or latch member 31 carried by a horizontal shaft 31a having handles 31b, see particularly Figs. 1 and 2, the crosshead 18 may be temporarily held in elevated position, whereupon continuing rotation of the crankshaft 28 and reciprocation of the connecting rod may take place without effecting the vertical reciprocation of the crosshead 18 and its attached cupping or shaping heads 19.

The crankshaft 28 carries at its end opposite the crank arm 28a, a balance wheel 32. This shaft also carries a cam 33. A cam roller 33b is carried by the outer end of a supporting arm 33c. This roller is held in fixed position in engagement with the cam track of cam 33, see Fig. 7. The shaft 28 is provided adjacent the balance wheel 32 with a sprocket 34, the sprocket being connected through the medium of a sprocket chain 35

with a smaller sprocket 36 carried by the driven shaft of a gear reducing unit 37. This unit is connected by means of suitable shafting and couplings to an electric motor 38, the motor and gear reducing unit being mounted upon a base 39 which rests upon the base portion of the sub-frame 16. The base 39 is adjustable lengthwise of the sub-frame base by an adjusting screw 40 which is provided for the purpose of maintaining the drive chain 35 taut. During its adjusting movement, the base 39 is maintained in proper alignment by means of keepers or guide members 41. The crankshaft 28 also carries a cam 33a which, as shown, is not connected with the remaining structure but which may be operatively connected in place of the cam 33 if a shorter stroke is desired. The cam 33 is designed to effect a nine inch stroke, whereas the cam 33a is designed for producing an eight inch stroke.

The crosshead 18, as shown, is a unitary structure carrying at one end the cupping heads 19 and may be swung about the vertical shaft 30 in a horizontal plane when the latch 42, see particularly Figs. 1 and 5, is released from engagement with the fixed circular plate 43 which is mounted upon the upper end of the slide 18a. The main body portion or frame of the crosshead 18 carries an auxiliary adjustable frame 44 upon which an electric motor 45 is mounted. The electric motor 45 is provided for the purpose of rotating or driving the cupping heads 19. The motor shaft carries a driving pulley 46 which is connected by a belt 47 to a pair of driven pulleys 48 mounted upon separate shafts carried by the crosshead. Thus, by loosening the bolt and nut 49, the auxiliary frame for the motor may be adjusted lengthwise to maintain the drive belt 47 taut.

As stated previously, the improved cupping or shaping heads 19 are mounted upon the end portion of the crosshead at the end thereof which is opposite to the motor 45. The crosshead 18 carries a vertically disposed fixed plate 50 whose upper and lower edges are grooved at 50a. The upper groove is adapted to receive a substantially V-shaped projection 51a formed on a cupping guide 51, as clearly seen in Figs. 1, 5 and 7. The cupping head guide 51 is provided with a pair of spaced substantially U-shaped brackets 52, which brackets carry the dual cupping heads 19. When the guide 51 is assembled with the plate 50, a gib or key 53 is slid into place in the lower slot 50a and is held in position by means of bolts or cap screws 54, one of which may be seen in Fig. 7. The opposite ends of the cupping head guide 51 carry substantially V-shaped plates 55 which are bolted to the guide. An adjusting screw 56 is passed through each of the plates 55 and engages the crosshead plate 50. Thus, by adjusting the screws 56, the cupping head guide 51 may be adjusted lengthwise relative to the plate 50 and laterally of the crosshead 18 and its supported pair of cupping heads 19 in a horizontal plane.

Both of the cupping heads 19 are of the same construction and, therefore, only one of the heads will be described. The cupping head unit comprises a tubular casing 57 which extends downwardly through the bracket 52 and has an annular flange 57a at its upper end which rests upon the upper edge of the cupping head guide 51 and the bracket 52. The casing 57 may be vertically adjusted relative to the bracket 52 and held in any desired adjusted position by a bolt or cap screw 58 which is located in a slot 52a formed in the bracket. A circular casing or housing

shown as a whole at 59 is secured to the lower end of the tubular member 57, said casing 59 being in two parts and providing means for housing and supporting the cupping rollers and associated parts of the cupping head. A rotatably mounted sleeve member 60 extends vertically through the tubular member 57 and has fixedly mounted upon its upper end, above the cupping head guide 51, a pulley 61. The sleeve 60 carries an internal non-rotative sleeve 62 through which extends a shaft or spindle 64 which carries at its lower end, tumbler-engaging and centering means, such as the foot or button 63. The upper end of the shaft or spindle 64 is enlarged at 64a to engage or seat upon a shoulder formed interiorly of the sleeve 62. The shaft or spindle 64 is adapted for vertical reciprocating movement in the sleeve 62 and is normally urged downward by a coiled compression spring 65, the spring engaging at its upper end, a cap 66 which is threaded onto the sleeve 62. A rod 67 is threaded through the cap 66 and is provided with a knurled operating handle 67a located above the cap 66. The spring 65 serves as a cushion for the spindle 64 and its foot or button 63 and the adjustable rod 67 provides stop means engaged by the upper end 64a of the spindle when the cupping head moves relative to said spindle. The position of the cupping head with relation to the position of the projectable tumbler-engaging and centering means may be varied by suitable adjustable means, such as that shown in Figs. 5 and 7. Such means comprises, as shown, a pair of horizontally disposed spaced parallel arms 73 and 74. The lower arm 73 is bolted at 73a to the tubular casing 57 and carries a pair of upwardly projecting threaded studs 75. The upper arm 74 is fixedly attached to the upper end portion of sleeve 62 and the threaded portions of the studs extend through openings formed adjacent opposite ends of this arm. Adjusting and lock nuts 75a are associated with the studs above and below the arm 74 which permit adjustment of the sleeve 62 relative to the remainder of the cupping head unit so as to set or adjust the cupping heads for tumblers T or other glassware of different heights.

It will be understood that the shaft or spindle 64 normally does not rotate but is free to turn in the sleeve 62 when pressure is applied thereto through the medium of the engagement of the tumbler-engaging and centering means 63 with a tumbler T.

The sleeve 60 is adapted to be rotated by the pulley 61 which is driven by means of a belt 68 from the reduced portion of the pulley 43, see Figs. 1 and 5. It is to be understood that the upper or cap portion 59a of the circular casing 59 does not rotate but that the lower portion 59b of said casing, which houses the gearing to be described below, is capable of rotation. Such rotation is imparted to the lower portion 59b of the circular casing by the sleeve 60 to which it is secured by a lock ring or ring nut 76, see Figs. 5 and 6. The sleeve 60 extends through and is rotatable relative to a fixed gear or pinion 69 which is secured by bolts 69a to the cap portion 59a of the casing 59, see Fig. 6. This gear or pinion 69 is in mesh with a plurality of driven gears or pinions 70, five such being shown. The gears 70 are mounted upon short shafts 71 which project downwardly through openings formed in the rotatable portion 59b of the casing. Each shaft 71 carries at its lower end, a cupping or shaping roller 72 which, as shown, is of substantially frusto-conical form having a concave outer

surface or face. The gears 70 are of somewhat smaller diameter than the fixed gear 69 and as the casing portion 59b is rotated around the fixed gear 69, the smaller gears 70 are driven at high speed, thus causing the shafts 71 and their cupping rollers 72 to rotate at high speed independently of the cupping head and while said head is also rotating.

Suitable anti-friction ball bearing assemblies 71 and 73 are provided between the rotatable sleeve 60 and the tubular member or housing 51 of the cupping head unit. Lubricant is supplied to the parts through fittings 79 and 80, see Fig. 5, and suitable lubricant-retaining means are provided at appropriate places to prevent the escape of the lubricant.

The releasable latch member 42, previously referred to, is provided with a compression spring 42a and the keeper pin 42b which permits the release of the latch to allow the crosshead and the cupping or shaping head units to swing about the shaft 38 in the event any undue pressure is applied to the cupping heads during the operation of the machine.

It is desirable to maintain the concave outer surfaces of the shaping or cupping rollers 72 polished and free of foreign matter at all times. For this purpose, see Fig. 6, the lower portion 59b of the casing is provided with a plurality of spaced depending arms 81 whose lower ends carry a band or skirt-like strip or piece of felt or other suitable fabric 82. The depending arms 81 are shaped at their lower end portions in a manner which will maintain the band of felt in intimate contact at all times with the surfaces of the rollers. The arms and their supported band are preferably removably attached to the casing portion 59b by screws or the like 81a. The fabric band or strip 82 may be easily removed from the arms 81 and replaced by a new piece when desirable.

In Fig. 1 the automatic shaping or cupping machine is shown as positioned in operative relationship with the conveyer of a glazer, indicated as a whole at G. The glazer conveyer is of conventional form and comprises a series or plurality of formers F arranged in spaced relation for supporting individual tumblers T and for continuously transporting such tumblers. As seen in this figure, the main body portion of the automatic cupping machine is positioned at one side of the glazer conveyer G with the dual rotatable shaping or cupping heads 19 overlying the path of travel of the conveyer formers F.

In Fig. 3 there is shown in detail the planetary arrangement of the gearing for rotating the shaping or cupping rollers 72 of one of the cupping heads, the central non-rotative gear 69 being surrounded by the five rotatable smaller gears 70. It will be understood that the lower casing portion 59b rotates as indicated by the arrows in Fig. 3 and that each of the smaller gears 70 rotates independently of the rotation of the casing and while the latter is rotating.

The schematic view of Fig. 12 serves to indicate by arrows, the rotative movement of the dual heads and the independent rotative movement of the shaping or cupping rollers, as well as the progressive or advancing movement of the heads during this rotation.

The schematic and layout views of Fig. 9, 10 and 11 illustrate the cycle of movement of the cupping heads and of the operating cam 33. Fig. 9 indicates by arrows, the cycle of movement of the dual shaping or cupping heads 19. These

two heads as shown in solid lines are at the station or location "0-0" on the conveyer, corresponding to the "0" sector of the cam 33, shown in Fig. 11 at which point the crank arm 28a is in horizontal position as also indicated at "0" in Fig. 11, with the cam roller 33b being at position "0" within the cam groove or slot of cam 33. The downward movement of the crank arm 28a is represented by "0-1-2-3-4-5-6-7-8-9-10-11-12," these points showing the different elevations of the cupping heads proper. The cupping stroke is six inches down and six inches up. The remainder of the stroke is for the return movement of the cupping heads to complete a cycle at a somewhat faster speed due to the shape or design of the cam track or groove of cam 33. It will be understood that the cupping heads and their rollers descend the full six inches, whereas the spindle or rod 64 carrying the tumbler-engaging and centering means 63 does not travel as far as the heads and reaches the lower end of its stroke between stations 3 and 6. The spring 65 is compressed by the spindle during its movement between stations 3 and 6. As the cupping heads now move upwardly, the spindle 64 returns to its upper position during its travel from station 6 to station 9. This action is clearly illustrated in Fig. 10.

The balance wheel 32 begins to function at station 1, thus by the time the cupping heads are in their lowermost positions, the momentum of the balance wheel will assist in the elevation or raising of the cupping heads 19. It will be understood that the shaping or cupping of the tumblers T occurs between stations 3 and 6, whereas these cupping heads, that is the shaping rollers thereof, move away from the pair of tumblers T between stations 6 and 9, see Figs. 9 and 10. In these figures the movement or travel of the tumbler-engaging or centering members 63 is indicated by arrows.

It will be understood that the stroke of the crank arm 28a is twelve inches, whereas the movement of the cupping heads 19 is nine inches, in accordance with the particular operating cam 33 being used.

In Fig. 11 the relative movements and locations of each of the three units, namely the crank arm 28a, the cam roller 33b and the balance wheel 32, are indicated through one-half revolution or travel of a complete cycle of twelve inches.

The operation of the machine or apparatus of the present invention is substantially as follows:

As stated above, the automatic shaping or cupping machine of the present invention is adapted to shape or cup a pair of spaced glass tumblers which are traveling in a series on the formers F of the conveyer of a glazer without interrupting or retarding the travel of said tumblers on said conveyer. The machine is placed at one side of the conveyer of a glazer G as shown in Fig. 1 of the drawings, with the dual rotating shaping or cupping heads 19 of said machine arranged in line and overlying the conveyer so that the heads may be moved into and out of engagement with separate glass tumblers and move along with said tumblers during their travel to perform the shaping or cupping operation on the tumblers.

With the glazer conveyer traveling at its normal speed and supporting and transporting a plurality of spaced glass tumblers, the electric motors 38 and 45 are started in operation to effect the operation of the shaping or cupping machine. The electric motor 38 drives the reduction gearing housed in gear box 37 and through

the connections described above, effects the rotation of the crankshaft 28, cam 33 and crank arm 28a, the latter being connected through the mechanism previously described with the crosshead 18 to move said head up and down to impart a like motion to the dual cupping heads 19 and to advance the cupping heads at the same speed in a forward direction as the speed of movement of the conveyer. At the same time, the electric motor, through the mechanical connections described above, effects the rotation of the dual heads 19 and the rapid rotation of the five cupping rollers 72 of each cupping head. As clearly seen in the schematic views, particularly Figs. 9 and 10, the spindle 64 is projected downwardly until the tumbler-engaging and centering member 63 thereof contacts the inner surface of a tumbler base, whence the projection ceases and the spindle is cushioned by the spring 65. At the same time, the shaping or cupping rollers 72 are moved downwardly into engagement with the upper portion of a tumbler T to apply pressure in downward and inward directions to cup the same. It will be understood that the tumbler-engaging means 63 and the five shaping rollers 72 of both cupping heads move in unison. During the engagement of the members 63 and 72 with a pair of spaced tumblers T, the heads 19 travel forwardly or along with the glazer conveyer. The rollers are gradually released from engagement with the tumblers, as are the members 63, this occurring during the elevation of the crosshead 18 and the dual shaping or cupping heads 19 due to the formation and rotation of the cam 33. A cycle of movement of the pair of cupping heads 19 is completed by said heads shifting rearwardly above the conveyer at a somewhat faster speed than their advance movement and then shifting downwardly again at a slower rate of speed until the parts of the dual heads engage another pair of spaced tumblers and travel through another complete cycle of operations. The cycle of movement of the cupping heads 19 is controlled or governed by the crankshaft 28 and associated parts, and by the cam 33 with which the cam roller 33b is in operative engagement. It will be understood that the dual cupping heads 19 and the rollers 72 are constantly rotated at constant speeds through the medium of power derived from the electric motor 45 and the associated drive mechanism and gearing.

The movement of the machine is coordinated with the speed of travel of the conveyer with which it is associated so that the dual shaping or cupping heads rapidly and efficiently perform shaping or cupping operations on successive pairs of tumblers which are being transported by the conveyer.

The machine or apparatus of the present invention is fully automatic and the parts thereof are adjustable so as to accommodate the machine to glass tumblers or other glassware of different height and which may be arranged on a conveyer in different spaced relationship.

Having thus described the invention, what is claimed is:

1. An automatic cupping machine adapted for association with a glazer conveyer for conveying glass tumblers, comprising a supporting base, a sub-base adjustably mounted on the supporting base, an upright standard carried by said sub-base, a crosshead carried by said standard, a pair of rotatable cupping heads carried by said crosshead, a plurality of high speed rotatable concave rollers carried by each of said cupping heads,

means forming a part of each of the cupping heads for centering and maintaining a tumbler in position to be engaged by the rollers of the head, means for moving the centering means into engagement with the tumbler, means for rotating the cupping heads and the plurality of rollers of the heads, and means for moving the heads into and out of engagement with a pair of spaced tumblers and simultaneously advancing said heads as the tumblers are advanced by the glazer conveyer.

2. In a machine for cupping glass tumblers or other articles on a moving conveyer wherein said machine is located at a side of the conveyer and has a portion thereof overhanging and in cooperative relationship with the tumblers being moved by said conveyer, a supporting base, an upright sub-base adjustably mounted on the supporting base, a vertical slide base extending upwardly from the sub-base and mounted for reciprocating movement thereon, a crosshead carried by the vertical slide base and movable in a vertical plane relative to said slide base, a pair of rotatable cupping heads mounted at one end of said crosshead and overlying the moving conveyer, each of said cupping heads including a plurality of high speed rotatable concave rollers arranged in a circle and tumbler-engaging and centering means located within the circle and adapted to be projected downwardly beyond said rollers at predetermined times, means for rotating the cupping heads and the rollers of the cupping heads, means for projecting the centering means into engagement with a tumbler at predetermined times, and means for moving the cupping heads into and out of engagement with a pair of spaced tumblers for cupping the same and for simultaneously advancing said heads as the tumblers are advanced by the conveyer.

40 3. A machine according to claim 2, wherein the supporting base is provided with casters to permit the machine to be moved over a supporting surface, and wherein the supporting base is provided with adjustable surface-engaging supporting means for elevating the machine to remove said casters from engagement with the supporting surface.

45 4. A machine according to claim 2, wherein the cupping heads are adjustable toward and away from one another to compensate for different spacing of the tumblers on said conveyer.

50 5. In a machine for cupping glass tumblers or other articles on a moving conveyer wherein said machine is located at a side of the conveyer and has a portion thereof overhanging and in cooperative relationship with the tumblers being moved by said conveyer, a supporting base, an upright sub-base adjustably mounted on the supporting base, a vertical slide base extending upwardly from the sub-base and mounted for reciprocating movement thereon, a crosshead carried by the vertical slide base and movable in a vertical plane relative to said slide base, a pair of rotatable cupping heads mounted at one end of said crosshead and overlying the moving conveyer, each of said cupping heads including a plurality of high speed rotatable concave rollers arranged in a circle and tumbler-engaging and centering means located within the circle and adapted to be projected downwardly beyond said rollers at predetermined times, means for rotating the cupping heads and the rollers of the cupping heads, means for projecting the centering means into engagement with a tumbler at predetermined times, and means for moving the cupping heads

11

into and out of engagement with successive pairs of tumblers to cup the same and for simultaneously advancing the heads through a complete cycle in coordination with the movement of the tumbler-carrying conveyer.

6. A machine according to claim 5, wherein cam-actuated means advances the cupping heads through a portion of their cycle of movement at the same speed as the speed of travel of the tumblers and conveyer and returns the same through another portion of said cycle at a speed greater than the speed of travel of the conveyer.

7. A machine according to claim 1, wherein means is provided for maintaining the concave surfaces of the rollers of the cupping heads polished at all times.

8. A machine according to claim 2, wherein means is provided for maintaining the outer surfaces of the concave rollers of the cupping heads polished at all times.

9. A machine according to claim 2, wherein means is provided for maintaining the cupping heads in elevated position out of contact with the tumblers at predetermined times while at the same time permitting the continued rotation of said rollers.

10. In a machine for cupping glass tumblers or other articles on a moving conveyer wherein said machine is located at a side of the conveyer and has a portion thereof overhanging and in cooperative relationship with the tumblers being moved by said conveyer, a supporting base, an upright sub-base adjustably mounted on the supporting base, a vertical slide base extending upwardly from the sub-base and mounted for reciprocating movement thereon, a crosshead carried by the vertical slide base and movable in a vertical plane relative to said slide base, a pair of cupping heads mounted at one end of said crosshead and overlying the moving conveyer, each of said cupping heads including a plurality of rotatable concave rollers arranged in a circle and tumbler-engaging and centering means located within the circle and adapted to be projected downwardly beyond said rollers at predetermined times, means for rotating the cupping heads and the rollers of the cupping heads, means for projecting the centering means into engagement with a tumbler at predetermined times, and means for imparting a cycle of movement to the cupping heads in timed relation to the travel of the conveyer and supported tumblers whereby the rollers of the heads are moved into contact with a pair of spaced tumblers to cup the same and advanced with the tumblers while performing the cupping operation thereon, moved out of engagement with said tumblers and returned to positions to be engaged with successive tumblers.

11. A machine according to claim 10, wherein the return travel of the cupping heads is at a greater rate of speed than the advance travel thereof.

12. A machine according to claim 5, wherein the cupping heads are adjustable toward and away from one another to compensate for different spacing of the tumblers on said conveyer.

13. A machine according to claim 5, wherein the last-named means is cam-actuated means which advances the cupping heads through a portion of their cycle of movement at the same speed as the speed of travel of the tumblers and conveyer and returns the same through another portion of said cycle at a speed greater than the speed of travel of the conveyer, and wherein the

12

cupping heads are adjustable toward and away from one another to compensate for different spacing of the tumblers on said conveyer.

14. A machine according to claim 1, wherein the cupping heads are vertically adjustable to raise or lower the rollers thereof to accommodate tumblers of different heights.

15. A machine according to claim 2, wherein the cupping heads are vertically adjustable to raise or lower the rollers thereof to accommodate tumblers of different heights.

16. In a tumbler cupping apparatus adapted to be associated with a moving conveyer having formers for supporting a plurality of tumblers in spaced relation thereon, a cupping head located in position overhanging said conveyer, said head comprising a plurality of tumbler-cupping members for cupping successive tumblers carried by the formers, means carried by the cupping head for holding a tumbler in position on a former during the cupping operation, said tumbler-cupping members being a plurality of forming rollers adapted to engage the outside of the tumbler and said tumbler-holding means being an axially projectable member adapted to engage the inner surface of the bottom of said tumbler, means for projecting said last-named member into a tumbler, and means for rotating said cupping head and said tumbler-cupping rollers.

17. An apparatus according to claim 16, wherein the tumbler-cupping members are a plurality of circularly arranged rapidly rotating concave rollers and wherein the tumbler-holding means is an axially projectable spindle located within the circle and carrying at its lower end a tumbler-engaging and holding foot.

18. An apparatus according to claim 16, wherein means is provided for moving the cupping head into engagement with a tumbler, for moving said head along with said tumbler, for disengaging the head from the tumbler, and for returning the head to its starting position in readiness to be engaged with the next successive tumbler.

19. An apparatus according to claim 16, wherein the tumbler-cupping members are a plurality of circularly arranged rapidly rotating concave rollers, wherein the tumbler-holding means is an axially projectable spindle located with the circle and carrying at its lower end a tumbler-engaging and holding foot, and wherein means is provided for moving the cupping head into engagement with a tumbler, for moving said head along with said tumbler, for disengaging the head from the tumbler, and for returning the head to its starting position in readiness to be engaged with the next successive tumbler.

20. An apparatus according to claim 16, wherein in the cupping head is rotated and wherein the cupping members are positively rotated at high speed independently of the rotation of the head.

21. An automatic cupping machine adapted for association with a glazer conveyer for conveying glass articles, comprising a supporting base, a sub-base adjustably mounted on the supporting base, an upright standard carried by said sub-base, a supporting arm carried by said standard, a rotatable cupping head carried by said arm, a plurality of high speed rotatable concave rollers carried by said cupping head, means forming a part of the cupping head for centering and maintaining a glass article in position to be engaged by the rollers of the head, means for moving the centering means into engagement with the article, means for rotating the cupping head

and the plurality of rollers of the head, and means for moving the head into and out of engagement with a glass article and simultaneously advancing the head as the article is advanced by the glazer conveyer.

22. In a machine for cupping glass articles or other articles on a moving conveyer wherein said machine is located at a side of the conveyer and has a portion thereof overhanging and in cooperative relationship with the articles being moved by said conveyer, a supporting base, an upright sub-base adjustably mounted on the supporting base, a vertical slide base extending upwardly from the sub-base and mounted for reciprocating movement thereon, a supporting arm carried by the vertical slide base and movable in a vertical plane relative to said slide base, a rotatable cupping head mounted on said arm and overlying the moving conveyer, said cupping head including a plurality of high speed rotatable concave rollers arranged in a circle and article-engaging and centering means located within the circle and adapted to be projected downwardly beyond said rollers at predetermined times, means for rotating the cupping head and the rollers of the cupping head, means for projecting the centering means into engagement with an article at predetermined times, and means for moving said cupping head into and out of engagement with an article for cupping the same and for simultaneously advancing said head as the article is advanced by the conveyer.

23. In a machine for cupping glass articles or other articles on a moving conveyer wherein said machine is located at a side of the conveyer and has a portion thereof overhanging and in cooperative relationship with the articles being moved by said conveyer, a supporting base, an upright sub-base adjustably mounted on the supporting base, a vertical slide base extending upwardly from the sub-base and mounted for reciprocating movement thereon, a supporting arm carried by the vertical slide base and movable in a vertical plane relative to said slide base, a rotatable cupping head mounted on said arm and overlying the moving conveyer, said cupping head including a plurality of high speed rotatable concave rollers arranged in a circle and article-engaging and centering means located within the circle and adapted to be projected downwardly beyond said rollers at predetermined times, means for rotating the cupping head and the rollers of the cupping head, means for projecting the centering means into engagement with an article at predetermined times, and means for imparting a cycle of movement to the cupping head in timed relation to the travel of the conveyer and supported articles whereby the rollers of the head are moved into engagement with successive articles to cup the same and are advanced with the article while performing the cupping operation thereon, moved out of engagement with said article and returned to position to be engaged with the successive article on the conveyer.

24. A machine according to claim 23 wherein said last-named means includes cam-actuated mechanism which advances the cupping head through a portion of its cycle of movement at the same speed as the speed of travel of the article and conveyer and returns the same through another portion of said cycle at a speed greater than the speed of travel of the conveyer.

25. A machine according to claim 23 wherein means is provided for maintaining the concave surfaces of the rollers of the cupping head polished at all times, said means comprising an annular polishing member surrounding and engaging the said circle of concave rollers.

26. A machine for cupping glass articles or other articles on a moving conveyer having a straight portion with which the machine is associated, comprising a supporting frame, an upright standard carried by the frame and reciprocably mounted thereon for movement substantially parallel to said portion of the conveyer, said upright standard being provided with a vertical guide, a slide mounted in said guide, a horizontally disposed arm carried by said slide and extending over said conveyer, a cupping head mounted on said arm for engaging successive articles on the conveyer, and means for simultaneously moving said slide downwardly and moving said upright standard in the same direction as the advancing conveyer so that an article on the conveyer will be engaged by the cupping head as it moves along with the conveyer.

27. A machine according to claim 26 wherein said last-named means includes a rotatable shaft provided with a crank arm and a cam for rotation therewith, a connecting rod connecting said crank arm and said slide, and cam-engaging means carried by said standard and engaging said cam.

28. A structure according to claim 27 wherein in said shaft is horizontally disposed and the crank arm is located at one end thereof, and a balance wheel disposed on the opposite end of said shaft.

29. A machine according to claim 26 wherein the cupping head includes a member for entering the article and holding it in position on the conveyer and a forming member for engaging the outer surface of the article.
